COMBINED ASH TRAY AND CIGARETTE EXTINGUISHER

Robert H. Adams, Sacramento, Calif.

Application October 27, 1955, Serial No. 38,592

Term of patent 14 years

(Cl. D85—2)

Fig. 2 is a side elevational view thereof;

Fig. 3 is a cross-sectional view thereof taken on line 3—3 of Fig. 1;

Fig. 4 is a cross-sectional view thereof taken on line 4—4 in Fig. 1; and

Fig. 5 is a cross-sectional view thereof taken on line 5—5 in Fig. 1.

I claim:

The ornamental design for a combined ash tray and cigarette extinguisher, as shown.
